UNITED STATES PATENT OFFICE.

THOMAS S. HOMANS, OF HEMPSTEAD, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,092,715.

Specification of Letters Patent. Patented Apr. 7, 1914.

Application filed June 18, 1912. Serial No. 704,442.

To all whom it may concern:

Be it known that I, THOMAS S. HOMANS, a citizen of the United States, residing at Hempstead, in the county of Nassau and 5 State of New York, have invented new and useful Improvements in Linotype-Machines, of which the following is a specification.

This invention relates to improvements in linotype machines and more particularly to 10 the mechanism controlling the delivery of matrices from the magazine, and the primary object of the invention is to provide simple and improved means for actuating the matrix controlling escapements whereby 15 certainty in the operation thereof is insured and overthrow of motion between the escapement actuating mechanism and the escapements is provided for.

To these and other ends, the invention 20 consists in certain improvements, and combinations and arrangements of parts, all as will be hereinafter more fully described, the novel features being pointed out particularly in the claims at the end of the specification.

In the accompanying drawing: Figure 1 represents a vertical section through portions of the magazine, escapement actuating mechanism and keyboard showing the improvements of the present invention applied thereto, the mechanism being shown in normal or inoperative position; Fig. 2 is a view 30 similar to Fig. 1 showing the escapement and its actuating mechanism in operated position.

Similar parts are designated by the same reference characters in the several views.

The present invention is applicable generally to escapement mechanisms of different types, and it is to be understood that the invention is not limited in this regard although the present improvements are shown in connection with an escapement of a novel form which forms the subject matter of a separate application and hence is not claimed herein.

The preferred embodiment of the invention is shown in the accompanying drawing and will be hereinafter described in 50 detail, but it is to be understood that the invention is not limited to the particular construction shown, as equivalent means may be provided for accomplishing the same results.

In the present instance, 1 designates the 55 lower or matrix delivery end of the magazine, the magazine having a channel for each row of matrices 2, and the escapement 3, one of which is arranged in the bottom of each matrix channel of the magazine, 60 controls the delivery of the matrices therefrom. The escapement shown may be briefly described as composed of a segmental member of substantially semi-circular form and forming dogs 4 and 5 at its ends to co- 65 operate with the ears or lugs 6 on the matrices, each escapement being adapted to oscillate about a fixed axis which is in substantial alinement with the ends of the escapement and is located in the matrix guid- 70 ing groove formed in the bottom of the magazine channel. The escapement is supported and guided in its oscillatory movements by a segmental bar 7 which extends transversely across the bottom of the maga- 75 zine and the escapement is returned automatically to initial position after each actuation thereof by a spring 8 which bears on a lug 9 on the escapement and has its end fixed in a projection 10 which is rigidly at- 80 tached to the magazine. A cover plate or guard 11 is also applied to the under side of the magazine and co-operates with the outer side of the segmental escapement to retain the same in co-operative relation with 85 the bar 7. A lug 12 projecting from that end of the escapement opposite to the end bearing the lug 9 serves to actuate the escapement in opposition to the action of the spring 8, the two positions of the escape- 90 ment being indicated in Figs. 1 and 2. Preferably, the under side of the actuating lug 12 of the escapement is formed with a beveled surface 13 for a purpose that will hereinafter appear. The key lever 14 95 may co-operate as usual with a vertically movable key bar 15, the latter co-operating with a bell-crank lever 16 the end 17 of which bears on and normally supports the cam yoke 18, the latter being fulcrumed on 100 the machine frame at 19 and bearing a cam 20 which is revoluble on a pivot pin 21 supported by the cam yoke. This cam is adapted to co-operate with the periphery of a continuously revolving roller 22 when the 105 respective key bar 15 is elevated by manipulation of the respective key lever, such movement of the key bar causing the bell-

crank lever 16 to operate in a manner to lower the cam yoke and thus permit the cam to come in contact with the roller, a projection 23 on the cam normally resting 5 against a toothed bar 24 to hold the cam in an inoperative position although disengaging from the bar 24 when the cam yoke is lowered.

A row of escapement actuating reeds 25 10 is provided to correspond with the row of escapements, these reeds resting on the vertically movable ends of the respective cam levers 18 and they are guided at their lower ends by the bracket 26. The upper portions 15 of the reeds 25 are guided by a bar 27 which prevents lateral displacement of the reeds, thus maintaining them in coöperative relation with the respective escapements, but each reed operates in a slot 28 in the bar 27 20 whereby the reeds may become deflected in the planes of their respective escapements. The upper end of each reed is formed with a beveled surface 29 which is adapted to co-operate with the beveled surface 13 of the 25 corresponding escapement actuating lug 12, and each reed is acted upon by a tension spring 30 which operates preferably to draw the reed in a diagonal direction downwardly to maintain it in proper relation to its respective cam yoke and to maintain its upper 30 end in operative relation to the respective escapement actuating projection. When one of the reeds is elevated by its respective cam yoke, the spring 30 will act to 35 hold the upper beveled end of the reed in contact with the corresponding actuating projection 12 on the respective escapement until the escapement has been actuated and caused to assume the position shown in Fig. 40 2 whereby the foremost matrix in the respective magazine channel is released by the dog 4 of the escapement and the following matrix is arrested by the dog 5 of the escapement, and when the escapement is so operated, the actuating lug 12 thereon will abut 45 against a stop 31 which is formed at the under side of the magazine. In operating the escapement in this manner, the force of 50 the spring 30 is sufficient to overcome the strength of the escapement-returning spring 8. However, when the escapement actuating projection 12 abuts against the rigid stop 31, further movement of the escapement is prevented and the excess motion or overthrow 55 of the reed is compensated for by a deflecting action of the upper end of the reed, which causes the latter to assume an inoperative position relatively to the respective escapement, the beveled surface on the upper end 60 of the reed riding toward the outer end of the projection 12 of the escapement as shown by the full lines in Fig. 2, the spring 30 yielding to permit such movement of the reed, and when the cam yoke returns to

initial position the reed will be restored to 65 initial position by the action of the spring 30, the escapement being restored by the operation of its spring 8.

I claim:—

1. In a linotype machine, the combination 70 of a magazine having a matrix controlling escapement, actuating mechanism thereof, and a reed operative by said actuating mechanism to engage and positively actuate the escapement to release a matrix and yieldable into an inoperative position relatively to the escapement to allow overmotion of the reed. 75

2. In a linotype machine, the combination 80 of a magazine having a matrix controlling escapement, actuating mechanism therefor, a member operative by said mechanism and coöperative with the escapement, and means for holding said member in operative relation to the escapement until the latter has 85 delivered a matrix and yieldable to permit said member to deflect laterally and assume an inoperative relation to the escapement and thereby allow overmotion of said member. 90

3. In a linotype machine, the combination 95 of a magazine having a matrix controlling escapement, actuating mechanism thereof, and a longitudinally movable reed operative by said mechanism and having a beveled surface to engage and operate the escapement to deliver a matrix and yieldable into a deflected relation to the escapement to allow overmotion of the reed after the latter has 100 operated the escapement. 100

4. In a linotype machine, the combination 105 of a magazine having a matrix controlling escapement, actuating mechanism thereof, a reed reciprocable by said mechanism, the reed and escapement having coöperative surfaces beveled diagonally of the direction of movement of the reed, and means for retaining such surface in operative relation to 110 actuate the escapement, and permitting a slipping action between such surfaces as the reed continues to operate after the escapement has delivered a matrix. 110

5. In a linotype machine, the combination 115 of a magazine having a matrix controlling escapement, actuating mechanism therefor, a reed reciprocable by said mechanism, the reed and escapement having coöperative surfaces beveled diagonally of the direction of movement of the reed, and means for retaining such surface in operative relation to 120 actuate the escapement, and causing deflection of the reed after the latter has caused delivery of a matrix by said escapement. 120

6. In a linotype machine, the combination 125 of a magazine having a matrix controlling escapement provided with a stop for arresting the movement thereof after releasing a matrix, and escapement actuating mecha-

nism embodying a reciprocable reed having a diagonally beveled surface coöperative with the escapement, and means yieldably retaining the beveled surface of the reed in position to actuate the escapement until the latter has engaged its stop and then permitting deflection of the reed.

In testimony whereof I have hereunto set my hand in presence of two subscribing witnesses.

THOMAS S. HOMANS.
